METHOD OF MAKING PUNCHES AND DIES

Robert J. Wilkie, Minneapolis, Minn., assignor to
 Continental Machine Specialties, Inc., Minneapolis, Minn., a corporation of Minnesota

Application February 11, 1939, Serial No. 255,893

7 Claims. (Cl. 76—107)

This invention relates to the art of making dies and refers particularly to a method of making cutting and punching dies.

In the past, the matrix or die proper generally has been cut from a piece or blank of stock directly to or very close to the outline of the die layout line; and in the ordinary machining processes used for this purpose, the part cut out, which is sometimes called the slug, was either reduced to chips or otherwise rendered unfit for use. This resulted in considerable waste inasmuch as the punch for the die had to be cut separately out of another piece of stock and very carefully machined to fit the die proper.

This past method of making a set of dies (punch and matrix) was also objectionable due to the excessive expenditure of labor necessary to properly cut and fit the parts.

This invention, therefore, has as one of its objects the provision of an improved method of making dies whereby the slug, which is the material cut from the blank in the roughing out of the die proper, may be used to make the punch, thereby effecting a considerable saving in time and material, as a single cutting operation roughs out the punch as well as the die proper from a single piece of material no larger than that required for the die proper.

More specifically, this invention contemplates simultaneously cutting the punch and die from a single blank of material in such a manner that an excess of material sufficient for properly finishing the edges of the punch and the die is left on both pieces.

This invention also contemplates a method of cutting the stripper for the punch simultaneously with the cutting of the punch and the die.

With the above and other objects in view which will appear as the description proceeds, this invention resides in the novel construction, combination and arrangement of parts substantially as hereinafter described and more particularly defined by the appended claims, it being understood that such changes in the precise embodiment of the hereinindisclosed invention may be made as come within the scope of the claims.

The accompanying drawing illustrates two complete examples of the physical embodiment of the invention constructed according to the best modes so far devised for the practical application of the principles thereof, and in which:

Figure 1 is a perspective view partially in section, showing the manner in which the cut is made;

Figure 2 is a vertical sectional view through a die and punch made in accordance with the method of this invention;

Figure 3 is a perspective view showing the punch and die directly after the roughing operation with the slug (from which the punch is made) removed from the die; and

Figure 4 is a vertical sectional view illustrating a method of cutting a stripper plate simultaneously with the cutting of the die.

Referring now more particularly to the accompanying drawing, in which like numerals indicate like parts, the numeral 5 represents a block or blank of stock of a size sufficiently large to be used as the matrix or die proper. In order to cut the die so that the slug may be used as a punch, a hole 6 is first drilled through the thickness of the block at an angle to an axis normal to the general plane of the block.

The angle at which the hole is drilled is sufficient to dispose the edge of the hole at the top face 7 of the block inside the die layout line 8 and the edge of the hole at the bottom face 9 of the block outside the die layout line. The thickness of the stock thus determines the angle at which the hole is drilled and also the diameter of the hole, it being desirable to keep the hole as small as possible.

After the hole has been drilled, a saw blade 10 is inserted through the hole. Any suitable type of power saw may be employed, although it is preferable to use a band saw (not shown) in which case the blade must be cut and welded.

The table of the saw, represented by the line 35 T, is tilted so that the saw blade passes through and substantially bisects the irregular plane connecting the layout lines at the top and bottom faces of the block. Hence, the cut is spaced inwardly from the die layout line at the top face 7 of the block, and outwardly of the die layout line at the bottom face 9 of the block. The sides of the hole 11 and of the slug 12 are consequently tapered, providing an excess of material 13 extending inside the die layout line at the top face 40 of the die, and an excess of material 14 at the bottom of the slug 12 extending outside the die layout line.

After cutting, the slug 12 is removed, as clearly illustrated in Figure 3. The edge of the hole in 50 the matrix or die proper, which has the excess material 13 overhanging the die layout line, is then accurately filed or trimmed down to the layout line perpendicularly to the face of the die to form the "land".

The slug 12 is transformed into the punch by centering the die on the larger face of the slug and inscribing its contour thereon. The edge portion 14 outside the line thus obtained is then 5 cut or filed off to form the straight side of the punch.

During the removal of the excess stock from the edge of the hole 11 and the edge of the slug, the starting hole disappears from the straight 10 side of the punch and the "land" on the die proper.

It is particularly significant that the slug or punch and the die proper are cut simultaneously from a solid block. This assures greater strength 15 as the grain of the stock may be matched after finishing the punch and die.

While it may be more feasible in most instances to use a saw for making the cut, it is understood that a cutting torch may be used, if desired. In 20 this event, it is, of course, unnecessary to drill a starting hole.

If the shape of the punch and the die and the nature of the material to be punched is such that a stripper is required, it may be produced simultaneously 25 with the roughing out of the punch and die. To this end, a plate 15 is secured to one side of the block 5, as shown in Figure 4.

A hole will then be cut in this plate to a shape 30 corresponding with that of the die layout line but sufficiently large to provide clearance for the punch.

From the foregoing description taken in connection with the accompanying drawing, it will be readily apparent to those skilled in the art, that this method of making a die is particularly well suited wherever the outline of the die is irregular and that a substantial saving in material and time is effected thereby.

What I claim as my invention is:

40 1. The herein described method of roughing out a punch and die from a single piece of stock and in such a manner that the roughed out punch and die both have an excess of stock overhanging the die layout line, which comprises: forming a starting hole through a blank at an angle to an axis normal to the face of the blank and with the edge of the hole at one face of the blank inside the die layout line and the edge of the hole at the opposite face of the blank outside 50 the die layout line; inserting a saw blade through said hole; and sawing through the blank at an angle to said axis with the saw-cut following the die layout line and extending inside the boundary defined by the die layout line at one face of the blank, and outside said boundary at the opposite face of the blank, the angle of sawing being different than that of the starting hole whereby the hole is substantially eliminated at opposite sides during the sawing.

55 2. The herein described method of making a punch and die which comprises: cutting a punch slug from a die blank with the surfaces of the cut tapered and the cut so related to the die layout line as to provide an excess of stock overhanging the die layout line at one face of the die and at one face of the slug; and removing at least a portion of said excess stock from the punch and the die so that the punch slug is movable through the hole in the die blank, said removal being such as to provide the punch and the die with clearance.

70 3. The herein described method of making a

punch and die which comprises: drilling a hole through a die blank at an angle to an axis normal to the general plane of the blank; inserting a saw blade through said hole; cutting a punch slug from the blank by sawing at an angle to 5 said axis and in such relation to the die layout line that the surfaces of the cut taper to provide an excess of material overhanging the die layout line at one face of the die and at one face of the punch slug; and removing said excess material so that the punch slug is movable through the hole in the die blank.

4. The herein described method of making the male and female parts of a die which comprises: cutting a piece from a blank of material to substantially the size and shape of the male part of the die and with the cut disposed at an angle to the face of the blank so that the perimeter of the piece at one of its surfaces is sufficiently larger than its perimeter at its opposite surface 15 to preclude passage of the piece through the hole in the blank; and accurately removing part of the side walls of the piece and the hole to fit the piece to the hole for smooth passage therethrough with the proper clearance for a punch and die. 20

5. The herein described method of making a punch and die which comprises: cutting through a blank which is to form the die substantially along but spaced from the die layout line and at an angle to an axis normal to the face of the 30 blank so that the area defined by the cut and coinciding in size and shape with the area defined by the die layout line lies on a plane between the faces of the blank and an excess of stock overhangs the die layout line at one face 35 of the piece thus cut from the blank and at one face of the blank; and removing said excess stock from both the blank and the piece to make the piece movable through the hole in the blank.

6. The herein described method of making a 40 punch and die and a stripper for the punch which comprises: removably securing a stripper blank to one side of a die blank; and simultaneously cutting a hole through said blanks with the surface of the cut tapered and the largest 45 end of the hole in the stripper blank, and with the cut so related to the die layout line as to provide an excess of stock overhanging the die layout line at one face of the die and at one face of the punch slug cut from the die blank 50 and so that the hole in the stripper blank is larger than the punch slug cut from the die blank.

7. The herein described method of making a punch and die which comprises: drilling a hole 55 through a die blank at an angle to an axis normal to the general plane of the blank; inserting a saw blade through said hole; cutting a punch slug from the blank by sawing at an angle to said axis less than the angle at which the hole 60 is drilled and in such relation to the die layout line that the surfaces of the cut taper to provide an excess of material overhanging the die layout line at one face of the die and at one face of the punch slug; and removing said excess material so that the punch slug is movable through the hole in the die blank, the difference in angularity between the drilled hole and the saw cut being sufficient to insure cutting away the drilled hole at the cutting faces of the punch 65 slug and die blank during the removal of said excess material.

ROBERT J. WILKIE.
